UNITED STATES PATENT OFFICE.

EDWARD L. DUNN, OF EAST ORANGE, NEW JERSEY, ASSIGNOR TO OTIS ELEVATOR COMPANY, OF JERSEY CITY, NEW JERSEY, A CORPORATION OF NEW JERSEY.

MECHANICAL INTERLOCK FOR ELEVATORS.

Application filed September 16, 1921. Serial No. 501,084.

To all whom it may concern:

Be it known that I, EDWARD L. DUNN, citizen of the United States, residing in East Orange, in the county of Essex and State of New Jersey, have invented a new and useful Improvement in Mechanical Interlocks for Elevators, of which the following is a specification.

My invention relates to improvements in mechanical interlocks for elevators, which keep the landing door or doors, other than that door opposite to which the elevator car is stopped, securely locked. Stopping of the car at a landing unlocks the door, and opening of the door of the landing opposite to which the car has been stopped locks the control mechanism of the car, preventing movement away from the said landing until the door has been closed.

An object of my invention is attained by the particular design of that part of the interlock mechanism on the car, whereby when the control mechanism has been brought to a neutral or off position to cause the car to be stopped at a landing, the coasting of the car in approaching the landing causes the above said part of the interlocking mechanism on the car to actuate that part of the interlock mechanism at the landing, unlocking the door at that landing, after which the door can be opened. The zone in which this unlocking takes place may be limited so that the car is level with the landing or so near to it that no difficulty is experienced in getting in or out of the car.

Another object of the invention is to simplify the construction of an apparatus of the above named character.

A further object of the invention is to make the door lock of the interlock mechanism reversible, so that the said door lock can be used either for right or left hand door. This object being attained without the use of additional parts.

A still further object of my invention in an elevator interlock mechanism is that it is adapted to be used with all types of car control means used in operating a car, and is also adapted to be used with all types of landing doors, any or all of which are used in the elevator art, which object is also attained without the use of additional parts to the interlock mechanism.

These objects I attain in the following manner, reference being had to the accompanying drawings, in which:

Figure 1 is a view in elevation of the door lock of the interlock mechanism, its parts being in the position they assume when the enclosure or hatchway door is locked.

Figure 2 is a view in elevation taken on the line *a*—*a* looking in the direction of the arrows in Figure 1.

Figure 3 is a view in elevation of the door lock cam, as seen from within the car, which is a part of the interlock mechanism carried by the car, the cam being shown in the position it attains while the car is running.

Figure 4 is a view of the other part of the interlock mechanism carried by the car.

Figure 5 is another view of the mechanism in Figure 4, a part therein shown in a fragmentary form, and another part in section.

Figure 6 is a view of a sufficient part of an elevator car to illustrate my invention, in position in front of a landing with the door closed and unlocked; the door being in a condition to be opened or the car to be moved away from the landing, the view embodying the present invention, and applied to a horizontally sliding door.

Figure 7 is a view in elevation of the interlock mechanism in Figure 6, looking at its end in this instance, and showing another part of the invention, not shown in Figure 6.

Figures 8 to 11 inclusive, illustrate the several positions of the door lock and door lock cam in the course of the operation of the interlocking mechanism.

Figure 12 illustrates the position of the door lock when tripped by hand, the door lock cam being shown in a running position.

Figures 13 and 14 are views illustrating the door lock with different types of sliding doors and their points of contact with the door lock in each individual case.

Figure 15 is a view of a sufficient part of an elevator car to illustrate my invention, applied to hand wheel car control, and showing means to lock the hand wheel, that part only of the present invention of an interlock being shown to illustrate its connection with the present control, the other parts of the

interlock mechanism being the same as shown in Figure 6, the said parts being in the same position as they are shown in Figure 6, when the means for locking the present control is in the position as shown in the present figure, the enclosure or hatchway door being in a condition to be opened in this case as related in the description of Figure 6.

10 Figure 16 is a view illustrating my invention applied to hand rope control, showing means to prevent operation of the said control, that part only of the interlock mechanism being shown to illustrate its connection with the present control, further explanation of the remaining parts of the invention being the same as given in the description of Figure 15.

15 Figure 17 is a view illustrating my invention applied to hand lever car control mechanism, illustrating the connection of a part of the interlock mechanism with the present control, further explanation of the remaining parts of the invention and position of the same, when the controlling means is in the off or neutral position, being substantially as told in the description of Figure 15.

20 Figure 18 is a view illustrating means for unlocking the door lock, to allow the enclosure or hatchway door to be opened independently of opening by means of the interlock mechanism on the car, the view shown being that seen from within the car, which car is not shown, the means for unlocking the door lock being actuated by means from the landing side, adapted to project through an opening in the wall between the hatchway and hall.

25 Figure 19 is a view in elevation illustrating the application of the door lock of the interlocking mechanism with a swinging door.

30 Figure 20 is a view in elevation of the intermediate locking mechanism, shown mounted in the Figure 19, looking at its front, which mechanism is used in the case of swinging doors with the present invention of an interlock, the said mechanism being shown locked.

35 50 It will be noted that the figures embodying an enclosure or hatchway door are all of the horizontal sliding type with the exception of the door in Figure 19; this is for no other reason than that the present invention can be as well described with this type of door as any other. Its adaptation to other types of sliding doors will be described in connection with Figures 13 and 14.

55 60 Like reference characters denote similar parts in all of the figures.

Reference being had to Figures 1 and 2, therein is shown a door lock, A, which is a part of the present invention of an interlock, and which comprises two movable parts, such as a ratchet, 1, and a pawl, 2;

held in place between two stationary parts, namely a back cover plate, 3, and a front cover plate, 4, the ratchet being carried upon a horizontal pivot pin, 5, which pin is riveted to the back plate. The pin, 5, and another pin, 6, likewise riveted to the back plate, are tapped out for the reception of screws, 7 and 8, which in turn hold the front cover plate, 4, in place. To the back plate, 3, there is also riveted another pin, 9, which is adapted to project into a slot, 10, formed in the ratchet, the purpose of the pin being to prevent throwing of the ratchet beyond its locked and unlocked positions. The ratchet has three forked ends or slotted openings, 11, 12 and 13. These make the lock adaptable to all types of sliding doors.

The ratchet is designed with an unbalanced weight, 14, to cause it to rotate by the unbalanced weight due to gravity, the vertical line of its center of gravity not passing through its center of gravity, as will be explained hereinafter. The pawl, 2, is carried upon a horizontal pivot pin, 15, and is free to turn thereon, it being shouldered at both ends, and is removable, the pin being received by the back plate, 3, to the extent of one of its shoulders, the front plate resting against its other shoulder, by means of an opening in the said cover plate for that purpose, the pin virtually bridges the two plates and is held in place by the same. The pawl is also unbalanced by means of its full arm, 16, which extends out from underneath the front plate, 4, and to which arm is attached a roller, 17, held to the pawl by means of a shoulder screw, 18, inside the roller, the screw being secured to the pawl. The other arm, 19, of the pawl extends up underneath the front cover plate, and is adapted to engage the locking and unlocking points of the ratchet. The back cover plate, 3, is provided with four fastener holes, 20, 21, 22 and 23, for mounting the door lock to the floor landing or wall of the elevator well.

25 30 When the door lock is used with doors of the opposite hand, its ratchet is turned around, the reverse side becoming the observe side, likewise the pawl, a hole, 24, being provided in the front cover plate and a similar hole directly underneath it or registering with it in the back cover plate for the reception of the shouldered pin, 15, which carries the pawl.

35 40 Referring to Figure 3, therein is shown the door lock cam, B, to be mounted on the car and is adapted to actuate the pawl of the door lock through the movement of the car control mechanism, which will be explained hereinafter, the purpose at this time being to describe the cam, which comprises a cam, 25, its edges being turned inwardly forming a channel, a cross section of which is shown for illustration. One

45 50 side of the cam is straight throughout its 45 50

entire length, and the other side is straight in the vicinity of the middle of its length, its ends being turned outwardly therefrom. Extending outwardly on either side of the body part of the cam are two arms, 26 and 27, to the ends of which are loosely pivoted two links, 28 and 29. The free ends of the links are adapted to be loosely journaled at 30 and 31 to an angle iron plate, 32, secured to the car on its under side, as shown in Figure 6. A rod, 33, a fragmentary part of which is shown in Figures 3 and 4, and the whole of which is shown in Figure 6, is loosely journaled to the lower end, 34, of the cam 26.

Referring to Figures 4 and 5, therein are shown views of the remaining parts of the interlock mechanism, all of which are adapted to be fastened to the under side of a car platform by hangers, 35 and 36, the hanger, 35, consisting of two arms, 37 and 38, the arm, 37, centrally supporting at 39 a pair of bars, 40. At their ends, 41, and between the same is pinned a block, 42, to which block is pinned a forked connection, 43, which supports a rod, 44, which is adapted to project up through the car floor, and be connected to the car control apparatus. The forked connection, 43, and block, 42, provide in effect a universal joint and permit the parts constituting the connection to function properly regardless of the relative positions of the car control apparatus and hanger, 35. To the other ends, 45, of the bars, 40, and between the same is pinned a roller, 46, which is designed to rest in a pocket, 47, in the upper end of a slot, 48, formed in a cam plate, 49, the plate being loosely journaled on a shaft, 50, mounted in the arm, 38, of the hanger, 35, and the other hanger, 36. The cam plate at its upper end is in the form of a button, a boss, 51, also constituting a part of that end of the cam, the boss is encompassed by a washer, 52, on one side of which rests one end of a spring, 53, the other end of the spring, encompassing another boss, 54, on the upper end of a clutch lever, 55. The boss, 54, supports a washer, 56, on one side of which rests the other end of the spring, 53. The clutch lever is centrally pinned at 57 to the projecting end of the shaft, 50, in a slot formed in the shaft, the lower end of the lever adapted to engage a slot formed in a prong, 58, of the cam plate, the end of the lever being held in the slot by means of the expanding spring, 53, exerting a continuous pressure upon the other end of the lever. A chain, 59, is secured at one of its ends to the lever, and the other end to a lever, 72. The cause and time of operating the chain will be explained later. By means of the clutch lever, 55, results are obtained as if the cam were securely fastened to the shaft, 50, both

turning as one when moved. A collar, 60, is pinned at 61 to the shaft holding the cam in its place on the shaft.

To the shaft, 50, is pinned a crank arm, 62, to which is attached one end of the rod, 33, the other end of the rod having been spoken of heretofore in connection with the description of the parts shown in Figure 3.

The description will now proceed to describe the connection between the door lock, already described, adapted to be secured to the floor landing, and that part of the interlock mechanism adapted to be secured to the under side of the car, also already described, the latter to be interlocked with the door lock when the door is in its open position, all of which is shown with a car, to be operated by means of a car switch control mechanism, reference being had to Figures 6 and 7, and referring from time to time to Figures 8 to 11, inclusive, the latter figures illustrating parts of the interlock mechanism with their relative positions during the course of the interlock operation.

In the Figures 6 and 7, therein is shown a horizontal sliding door, D, one end of a door iron, 63, being secured thereto, the other end having engagement with the fork, 12, of the door lock ratchet, by means of a pin, 64, secured to the door iron, the pin projecting into the fork and held thereto, the door being closed but unlocked in the figures.

Saying nothing further at this time relative to Figures 6 and 7, I will now proceed to describe the conditions while the car is running.

When the car is running the door lock cam assumes a running position, the cam being operated by the car control mechanism, as will be told later. The door lock is locked during the running of the car, locking the enclosure or hatchway door, the position of the door lock and cam, assuming that as shown in Figure 8. The roller, 17, on the pawl, 2, of the door lock is adapted to project out into the path of the door lock cam, 25, and as is seen the roller is located centrally with the sides of the cam. Corresponding door locks located at the various landings throughout the rise of the car, assume the same position, all of which above description shows that while the car is running the cam on the car has no contact with the door locks although the roller on the pawl of the door lock projects out into the path of the cam.

Going back to Figures 6 and 7, therein is shown the car, at rest at a landing, the door lock cam, 25, being in a stopped position, likewise the car switch, 65. The rod, 44, is fastened at its upper end to the car switch, 65. Movement of the car switch lever, 66, in either direction to cause the car to move,

causes the rod, 44, to move, they both being connected to the same center, 67, the rod by means of a connection, 68, one end of which is fastened to the center, the other end 5 to the rod. The rod lifting the ends, 41, of the bars, 40, in an upwardly direction in its movement, the other ends, 45, of the rods being moved in a downwardly direction, the roller, 46, between these ends being moved 10 out of the pocket, 47, of the slot, 48, in the cam plate, 49. The slot in the cam corresponds in length to the relative length of throw of the car switch lever from both sides of its central position; this being so, 15 any throw of the car switch lever in either direction moves the roller to a position in the slot equal to the relative length of throw of the car switch lever by virtue of the equal leverage of the bars, 40, either side 20 of their points of connection, 39 to the arm, 37, of the hanger, 35. The roller, 46, will then be at some position in the slot during the running of the car as described with Figure 8, the position being that one relative 25 to the throw of the car switch handle. The car switch handle thrown to its extreme position in either direction would result in the roller being at the lowermost end of the slot. As the cam plate, 49, is connected to the shaft, 50, and also the crank arm, 62, in the manner already described, and the rod, 33, is fastened at one of its ends to the crank arm, and the other end to the door lock cam at 34, any throw of the car 30 switch lever to start the car results in a movement of all these parts, through the connections to the car switch lever already described and the said parts. The throw of the lever required to remove the roller, 46, from the pocket, 47, in the cam plate, 49, determines the length of movement of the door lock cam, from its present or stopped position to the position shown in Figure 8, which is its running position; further movement 35 of the roller in the slot does not result in any further movement of the door lock cam, the slot merely being means to allow further throw of the car switch lever without separation of the roller from the slot. 40 As there is invariably a slight lost motion either side of the central position of the car switch lever and the first control point in a car switch, and as the interlock mechanism is rigidly fastened throughout all parts to the car switch lever, the throw of the car switch lever from its central position towards the first control point of the switch will have resulted in withdrawing the roller, 46, from the pocket, 47, in the slot, and the door lock cam having assumed its running position before said control point has been reached, the pawl on the lock following the cam in the movement of the cam to reach the said running position by virtue of 45 the lack of balance of the lower arm, 16, of the pawl, the upper arm, 19, of the pawl engaging the notch or locking point, 69, of the ratchet of the lock, all of which shows that the door is securely locked before the car moves away from the landing at which it has been stopped. 50 Having described the interlock mechanism while the car was running, its position while the car was at rest at a landing, and its operation when the car was about to move away from the landing, the description will now proceed to describe the operation of the interlock when the car is approaching a landing to stop thereat. 55 The car approaches the landing at which it is to be stopped; the car switch lever is brought to its central position. In doing so the door lock cam is caused to assume a position as shown in Figures 6 and 9, this can be readily understood after reading the foregoing description of the operation of the interlock, the movements of the parts on the car being opposite at this time, the roller now being back in its position in the pocket, 47, of the slot, 48, of the cam plate, 49, having returned from the position it was at in the slot while the car was running. The car coasts, as is known, to arrive at the landing after the car control mechanism has reached its "off" position, the upper outwardly extending end of the cam, contacting with the roller, 17, on the pawl of the door lock, the car approaching the landing in an upward direction of car travel in this illustration. The door lock cam cams the pawl to one side in this approach freeing the upper arm, 19, of the pawl from the notch or locking point, 69, in the ratchet of the lock, the roller, 17, assuming a position on the cam as shown when the car is brought to rest, see Figure 9, or so nearly so, as the range of the cam is so limited that a level or nearly so stop is made with the landing. The ratchet is now unlocked, as it is free of the pawl engagement, and the door, of course, is also now unlocked and is in condition to be moved to be opened. When the car is approaching the landing in a downwardly direction of car travel, the pawl is cammed back by the cam engaging the roller, 17, on the lower extending end of the cam. In the movement of the door in opening after it has been unlocked, the door causes the ratchet and pawl to assume several positions, as there is contact between them through the intermediation of the door iron as heretofore described, in which Figure 9 shows the door lock and cam as seen in the Figure 6, the door being unlocked but still closed. Movement of the door in opening causes the ratchet to assume first the position as shown in Figure 10. It will be noticed that the pawl has not as yet changed its position from that in Figure 9. As that 60 part of the ratchet where the upper arm, 19, 65 70 75 80 85 90 95 100 105 110 115 120 125 130

of the pawl is now resting against, shown in Figure 10 is slightly convexly rounded, further movement of the door in opening, causes the rounded surface of the ratchet to 5 cam the pawl completely out of the notch, 70, and the roller, 17, of the pawl to be moved towards the straight side of the cam, the pawl having been cammed by the rounded surface out of the way of the notch, 70, 10 in the ratchet, the upper arm, 19 of the pawl engages the notch, 71, of the ratchet, see Figure 11, which is the final unlocked position of the door lock, and conversely speaking the final locking point of the control 15 mechanism. The feature of rounding the surface of the side of the notch, 70, is important in elevator service conditions. In the operation of the car, the car control mechanism is brought to its central or off 20 position to stop the elevator. If, as is sometimes the case by reason of wear or lost motion of the parts, the movement of the car control mechanism towards its central position serves to stop the elevator before the 25 control mechanism reaches its central position, it may be that the throw of the cam by the car control mechanism does not move the roller on the pawl far enough to one side to turn the pawl entirely free of the 30 path of the side of the notch, 70, in the ratchet; thereupon, when the door is being moved on its way to its full open position, and in doing so turns the ratchet, it may be found that the side of the notch, 70, strikes 35 the end, 19, of the pawl, the latter holds the ratchet against being further turned by the door, and, of course, also holds the door too from being further opened. By rounding the side of the notch, the rounded portion 40 serves to cam the end of the pawl out of the path of the ratchet. Then a further movement of the door will move the door iron out of the fork in the ratchet, in which it was in the beginning of the opening 45 movement of the door. The rounded surface has still another advantage; if the car control mechanism requires to be moved to center, and the near side of the cam, bearing against the roller, moves the roller sufficiently far to turn the pawl entirely free of the notch, the roller is probably left against the near or straight side of the cam. In order to allow for lateral play of the car in the elevator well, and possible inaccurate alignment of the positions of the parts of the lock, etc., it is customary to space the two sides or faces of the cam further apart from each other than the mere diameter of the roller. Consequently, when the 50 roller is against one of the sides of the cam, there may be considerable space, comparatively speaking, between the roller and the other side of the cam. Therefore, when the car control mechanism is moved to actuate the roller to turn the pawl, it may be found

that there is lost motion between the cam and roller. Whereas, where the rounded surface of the notch, 70, cams the pawl, the roller will be left practically equally spaced between the two sides of the cam. In that 70 position the movement of the car control mechanism will result in the cam actuating the roller earlier, which may be quite a desideratum in local car service, as the use of a door lock mechanism results usually in 75 slowing up the operation of the service of the elevator to some extent.

As the door iron on the door is now free of the fork of the ratchet with which it had engagement in the opening of the door, it is possible at this time to return the ratchet by hand to its locked position, but it will immediately return to its unlocked position when released, as it is unbalanced. The pawl cannot follow the ratchet when the ratchet is being returned by hand to its locked position, which it would have a tendency to do, as it is also unbalanced, because it is at that time prevented from being moved to engage and lock the ratchet. The above description points out the inability of a person on the floor landing to cause the ratchet to assume its locked condition merely by fumbling it in the manner mentioned. Any attempt to move the car control mechanism 95 at this time to start the car will result in the straight side of the cam, 25, contacting with the roller, 17, on the pawl, and the car control mechanism cannot be further moved, to cause the car to start, because the 100 end of the pawl is engaged in the notch in the ratchet at the point, 71, and the car control mechanism thereby is interlocked with the ratchet when the landing door is open 105 at which the car is at rest.

In the operation of closing the door, shown in Figures 6 and 7, the pin, 64, of the door iron, 63, again engages the fork, 12, of the ratchet. Where a quick getaway of the car from the landing is desired, the car control mechanism, 65, may be caused to assume a running position, when the ratchet has reached a position as in Figure 10, in the closing of the door, this position being when the door is nearly closed, the straight side throughout of the cam, 25, contacting with the roller of the pawl through operating the car control mechanism, and turning the pawl, causing the upper arm, 19, of the pawl, to engage the ratchet at its locking notch, 70. The point being brought out is, that the operator does not have to fully close the door before starting the car away from the landing, but instead can get the car away from the landing before the door is fully closed, and therefore without delay than would be the case if he had to close the door entirely before starting, the door being supposed to close to its entirety by its momentum; but if it is not 120 125 130

closed to its entirety in that movement, it will be locked, anyway, in the position it has moved to, and is prevented from being again opened from that position, except as herein described. Should the door be fully closed after the car has been moved away from the landing, the ratchet will be caused to assume the position in Figure 8; the upper arm of the pawl riding on the surface of the ratchet, between the locking points, 70 and 69, into which it drops due to it being unbalanced, see Figure 19.

An emergency release mechanism is also provided in connection with the interlock mechanism. It is located in the car, and within convenient reach of the operator, as shown in Figure 7, and comprises a lever, 72, chain, 59, clutch lever, 55, and spring, 53. The emergency release mechanism is designed to be operated if an occasion require, such, for instance, as a panic or fire, in which case, it may be desired to operate the car with open doors. The release is brought into play by bearing down on the end of the lever, 72, opposite the end to which the chain is secured, disengaging the clutch lever, 55, from the prong, 58, of the cam plate, 49, through the intermediation of the chain, 59, the chain running over a pulley, 73, held by a bracket, 74, secured to the under side of the car, the pulley acting as a guide to the chain. The cam plate, 49, is now free to turn on the shaft, 50, as it is no longer secured thereto by the clutch lever, 55, engaging its prong, 58. Any movement of the car control mechanism to start the car, results in the idle movement of the cam plate on the shaft, thereby allowing the car to be operated independently of the interlock mechanism.

Reference being had to Figure 12, the description to follow will refer to operating the car with an open door, in the course of making repairs, or for other reasons that would necessitate the same. In such a case the pawl, 2, of the door lock would be tripped by hand, assuring its open position by so doing, the car being out of the interlock zone at this time, the position of the car being below the landing, the door when opened would cause the ratchet, 1, of the door lock to assume its unlocked position by virtue of the connection of the door iron, 63, between itself and the door; the position of the pawl and ratchet being as shown in the figure, which is their normally unlocked position when the door is opened. Operating the control mechanism to cause the car to move by the open door would result in the door lock cam, 25, assuming its running position, the door lock cam being in a position relative to the pawl, 2, of the door lock as seen in the figure, the roller, 17, of the pawl, 2, being to one side or out of the path of the door lock cam when the car is running.

Figures 13 and 14, illustrate the adaptability of the door lock of the present invention of an interlock with the several types of sliding doors used in the elevator art. The first said figure showing the door lock with a right hand horizontal opening door, a right hand vertical "up" opening door, and a left hand vertical "down" opening door. The Figure 14 differs from the Figure 13, in that the ratchet and pawl have been changed to the opposite hand, the door lock to be used in this instance with a left hand horizontal opening door, a left hand vertical "up" opening door, and a left hand vertical "down" opening door. The door iron of each door being shown engaged with its particular fork of the ratchet, opening of which doors, the arrows indicating the direction, will result in the operation of the door lock as has heretofore been explained.

Reference being had to Figures 15 and 16, therein is shown respectively a hand wheel and a hand rope control means for elevator cars, to be used in each case with a locking means, such as a latch, 75, with the present invention of a door interlocking mechanism. The latch comprises a body part, 76, a bar, 77, and a lever, 78. As the car in each case is at rest, the locking means are locked with the car control means as seen in the figures, the bar, 77, in the case of the hand wheel control, is entered in a notch, 79, in the wheel, 80, and in the rope control means it is seen protruding out into the path of the control rope, 81, being in a position to be engaged by the stops, 82, on the rope should they be moved in an effort to start the car. The bar is moved out of its locking position with the control means by means of the lever, 78, an arm, 83, of the lever engaging a groove, 84, in the bar. An upward movement of the handle, 85, of the lever results in the control mechanism being unlocked. The rod, 44, one end of which is fastened to the lever, 78, through the connection, 68, the other end to the ends, 41, of the bars, 40, through the intermediation of the forked connection, 43, and the block, 42, is the rod, 44, spoken of in the description of Figures 6 and 7.

In the case of an elevator with hand lever control mechanism as shown in Figure 17, a lever, 86, is adapted to swing over a quadrant, 87. To the lever is secured a pin, 88, which engages a slot, 89, formed in the upper end of a connection, 90, the lower end of the connection being fastened to the rod, 44, at 91, the connection being pivoted at 92 to the control mechanism. Movement of the lever, 86, of the control mechanism to operate the car, C, causes its pin, 88, to travel in the slot, 89, in the connection, 90, the lower end of the connection swinging in an arc from its pivot pin, 92, in a

direction opposite to the throw of the lever, causing the rod, 44, in its movement and through which operation of the interlock mechanism is had to operate the same, as 5 in the description of the foregone means of car control.

In the case of enclosure or hatchway door to be unlocked other than through the means of the interlock mechanism, reference is 10 had to Figure 18, which illustrates such means, and which comprises a bar, 93, secured by its upper end, to the arm, 16, of the pawl, 2, of the door lock, its lower end supporting one end of a bar, 94, by means 15 of a pin, 95, secured to it and which engages a slot, 96, in the bar, the bar being fastened at its other end at 97 to an arm, 98, of a crank, 99, the other arm, 100, of the crank being adapted to be engaged by 20 a finger, 101, the crank to be pinned to the enclosure wall at 102, and the finger at 103, the finger to be turned by means of a key or other instrument from the landing side engaging the arm, 100, of the crank, lifting 25 in an upward direction the arm, 98, moving at right angle to the arm, 100, the arm, 98, carrying the bar with its movement, and which trips the pawl. The pawl being no longer engaged with the ratchet, the door 30 can be opened, the ratchet and pawl assuming their unlocked position, as seen in Figure 11.

In the case of an elevator where swinging enclosure or hatchway doors are used, 35 the present invention of an interlock may be used therewith, by using intermediate locking means. The door lock, A, of the present invention and its application to a swinging door being seen in Figure 19. The 40 intermediate lock, E, used in the present case comprises a ratchet, 104, pivoted at 105 and free to turn thereon, and a pawl, 106, pivoted at 107, and free to turn thereon, the ratchet and pawl to be enclosed by 45 a cover, 108, of which a section is shown thereof in the figure. An opening in the cover is provided at 109 to permit free movement of the arm, 110, of the ratchet, which arm extends out of the cover as shown, and 50 another opening at 111 to permit the door iron, 112, of the door, D, to protrude into and engage the lock. The lock is to be mounted on the door jamb at right angles to the door, four fastener holes, 113, 114, 55 115 and 116 being provided. To the arm, 110, of the ratchet of the intermediate lock, E, is loosely pinned a rod, 117, which rod extends downwardly, and is again pinned to a prong of the fork, 13, of the ratchet of 60 the door lock, A, which is to be secured to the wall below the landing sill, a side view of the door lock then being had by the observer but in the present figure it is shown in a front position to show more clearly its 65 connection to a swinging door. It will be

noticed that only one of the locking points on the ratchet of the door lock, A, is now used, namely, the locking point, 70, at which the pawl is now engaged. The pawl, 2, of the door lock, A, is tripped by the cam 70 mechanism in the same manner that has been heretofore described. Assuming that the pawl, 2, is no longer engaged with the locking point, 70, on the ratchet, through being tripped by the mechanism on the car, the 75 door may be caused to be opened, the door iron, 112, being engaged with the ratchet, 104, of the intermediate lock, E, at this time. A movement of it by the door will shift the ratchet by the opening movement of 80 the door to a position as shown in Figure 20, which is its locked position. The rim, 118, of the ratchet riding on the under edge, 119, of the pawl, during the shifting of the ratchet, after which the pawl falls downwardly engaging the ratchet as shown. The rod, 117, has been moved upwardly during the locking engagement of the ratchet and pawl of the intermediate lock, E, in the 85 opening of the door, and as it is connected at its lower end to the ratchet, 2, of the door lock, A, it has caused the said ratchet to assume its unlocked position. The door is now entirely unlocked and as has been told heretofore when the door lock is entirely 90 unlocked through movement of the door in opening, operation of the car from the landing cannot be had.

In the operation of closing the door, the door iron, 112, engages the round point, 120, of the pawl, camming the pawl upwardly, being lifted as a consequence from engagement with the ratchet, the door iron in the further movement of closing the door engaging the ratchet, 104, moving it over to 100 the position as shown in Figure 19. During this operation the rod, 117, has been forced downward returning the ratchet, 1, of the door lock, A, to its locked position. The pawl of the door lock, caused to engage the 105 ratchet at its locking point, 70, by the interlock mechanism on the car will result in the door being securely locked. It will be reflected that in my invention both the 110 ratchet and pawl are positively actuated, and without the aid of springs, which is greatly to be desired in a door lock mechanism, since springs to operate the ratchet and pawl of door lock mechanisms may not be invariably depended upon; and moreover, by reason of the position of the mechanism in the elevator well springs may not be merely visually properly inspected or 115 conveniently accessible to test. Again, if the door locking mechanism involving a spring 120 serve as a part of the mechanism between the car control mechanism and the door locking mechanism to interlock the car control mechanism and the door and the spring 125 will be happen not to function, the car control 130

mechanism could be operated with the door open or the door be opened when the car is not at that landing.

Having thus described my invention, 5 what I desire to secure by Letters Patent of the United States is:

1. In the art of elevators, door mechanisms, locks, a lock, comprising a ratchet, pivoted on a horizontal axis, out of equilibrium or unbalanced on its pivot, and free to be turned on its axis to be retracted by the movement of the door to an open position, and become disengaged from the door when in that position, and whereby the 15 ratchet will normally tend to turn on its axis to a retracted position, and a pawl, adapted to maintain the ratchet in its locked position, the pawl being also unbalanced, and means to hold the pawl out of engagement with the ratchet when the door is in 20 an open position.

2. In the elevator art, door locking mechanisms, locks, a lock, having a ratchet, with a notch therein, rounded at its free extremity and a pawl, adapted to engage and disengage the notch by the movement of the car control mechanism, the rounded extremity of the notch serving to strike and move the pawl free of its engagement in the 30 notch by the movement of the door to its open position.

3. In the elevator art, the combination of a hatchway door locking mechanism and a car control mechanism, comprising the ratchet of the door locking mechanism, means to lock the ratchet with the door in a closed position, and a mechanism connecting door locking and car control mechanisms, said connecting mechanism comprising among other parts, an upright rod, its upper end connected to the car control mechanism, and its lower end extended beneath the car and attached to a part of the 35 said connecting mechanism under the car, and a universal joint, between the rod and said part under the car.

4. In the elevator art, the combination of a hatchway door locking mechanism and a car control mechanism, comprising the ratchet of the door locking mechanism, means to lock the ratchet with the door in a closed position, and a mechanism connecting door locking and car control mechanisms, said connecting mechanism comprising 50 a horizontal rod, one end of which is connected to the door locking mechanism, its other end fastened to one end of a shaft, the shaft supporting at its other end a cam member, the cam member supporting one 55 end of each of two additional rods, an upright rod, its upper end connected to the car control mechanism, and its lower end extended beneath the car, and a universal joint between said upright rod and the other 60 ends of each of the said additional rods of 65

the said connecting mechanism under the car.

5. In the elevator art, the combination of a hatchway door locking mechanism and a car control mechanism, comprising the ratchet of the door locking mechanism, means to lock the ratchet with the door in a closed position, and a mechanism connecting the door locking and car control mechanisms, said connecting mechanism comprising among other parts, a cam, comprised of a pocket and an eccentric lost motion slot, the latter being of a length corresponding to the relative length of throw of the car control mechanism from both sides of its central position, a roller, adapted to be moved into and out of the pocket, and be guided in the slot, an equal arm lever, one end carrying the roller and the other end pivoted to the car control mechanism, whereby the slot serves to guide the roller, and a movement of the car control mechanism from its "off" position withdraws the roller from the pocket and releases the door lock mechanism. 75 80 85 90

6. In the elevator art, in the combination of a car control mechanism and a hatchway door locking mechanism, adapted to interlock the door locking and car control mechanisms, a device, adapted to release the interlock between the said two mechanisms, and allow the car control mechanism to be operated to operate the elevator with the door unlocked or open, as the case may be. 95

7. In the elevator art, the combination of an interlocking mechanism between the hatchway doors and car control mechanism, said locking mechanism including among other parts means whereby upon occasion the interlocking mechanism's other parts will be rendered inoperative, and allow the car control mechanism to be operated to operate the elevator with the doors open, said means comprising in effect a clutch adapted to free the interlocking mechanism's other parts between the car control and the door locking mechanisms. 100 105 110

8. In the elevator art, in the combination of an interlocking mechanism between the hatchway doors and car control mechanism, said locking mechanism including means whereby, upon occasion, it will render the interlocking mechanism inoperative, and allow the car control mechanism to be operated to operate the elevator with the doors open, said means comprising a lever, adapted to transmit motion between the car control and door locking mechanisms. 115 120

9. In the elevator art, the combination of an interlocking mechanism between the hatchway doors and car control mechanism, said locking mechanism including among other parts means whereby upon occasion the interlocking mechanism's other parts will be rendered inoperative, and allow the 125 130 135

car control mechanism to be operated to operate the elevator with the doors open, said means comprising in effect a clutch, comprised of a slotted member, and a clutch lever in the slot adapted to be freed of the slot to free the interlocking mechanism's other parts between the car control and the door locking mechanisms.

10. In the elevator art, the combination of an interlocking mechanism between the hatchway doors and car control mechanism, said locking mechanism including among other parts means whereby upon occasion, the interlocking mechanism's other parts will be rendered inoperative, and allow the car control mechanism to be operated to operate the elevator with the doors open, said means comprising in effect a clutch, comprised of a slotted member and a clutch lever, a chain adapted to be fastened to the clutch lever to run over a wheel and also fastened to an operating lever adapted to transmit motion through the chain for freeing the clutch lever from the slot, that the interlocking mechanism's other parts between the car control and the door locking mechanisms may be free.

11. In the elevator art, in the combination of a car control mechanism, means intermediate of the hatchway door locking mechanism and the door, and adapted to lock the car control mechanism, comprising a ratchet, and a pawl, adapted to engage and be disengaged from the ratchet, an arm on the door, adapted to engage the ratchet, and upon movement of the door to an open position to rotate the ratchet, and allow the pawl to engage it to prevent the car control mechanism from being operated and upon a movement of the door to its closed position to rotate the ratchet and disengage the pawl therefrom, and allow the car control mechanism to be operated.

12. In the elevator art, the combination of movable means adapted to lock the hatchway door, the car control apparatus, and a connection between the latter and the door locking means for transmitting the movement of the car control apparatus to said movable means, comprising a lost motion device, whereby the variable movements or throw of the car control apparatus in the operation of controlling the car results in transmitting to the door locking means only

one and the same fixed or limited or invariable throw, notwithstanding the variable throw of the car control apparatus.

13. In the elevator art, the combination of means to lock the hatchway door, the car control apparatus, and a lost motion connection between the locking means and car control apparatus, whereby the variable movements or throw of the latter in the operation of controlling the car transmits to the locking means only one and the same fixed and limited movement notwithstanding the variable movements of the car control apparatus, and a cam adapted to be actuated by the movement of the car control apparatus to unlock the door.

14. In the elevator art, the combination of a movable lock for the hatchway door, the car control apparatus, and a lost motion device between the lock and car control apparatus, whereby the variable throw of the car control apparatus in the operation of the car retracts the lock invariably to one and the same fixed or limited throw to unlock it, notwithstanding the variable movements of the car control apparatus in the operation of stopping the car, and a cam and opposite straight side or face, adapted to be actuated by the movement of the car control apparatus, the cam to unlock the lock and the straight side to restore it to its locked condition.

15. In the elevator art, the combination of a lock adapted to lock the hatchway door, the car control apparatus, and a lost motion connection between the lock and car control apparatus, whereby the variable throw of the car control apparatus in the operation of bringing the car to a stop moves the lock to one and the same fixed and limited position to unlock the door, regardless of the variable throw of the car control apparatus, and a cam and opposite straight side or face adapted to be actuated by the movement of the car control apparatus, the cam to unlatch and the straight side or face to latch the lock, the lock being adapted to be moved by the door in its movement to its full open position to bear against the straight side or face.

In testimony whereof, I have signed my name to this specification.

EDWARD L. DUNN.
